US0D1075752S

(12) **United States Design Patent** (10) **Patent No.:** **US D1,075,752 S**
(45) **Date of Patent:** **** May 20, 2025**

(54) **SMARTWATCH**

(71) Applicant: **Creek Wearable Technology Co., Ltd.**
Shenzhen (CN)

(72) Inventors: **An He**, Shenzhen (CN); **Kexin Tong**,
Shenzhen (CN)

(73) Assignee: **Creek Wearable Technology Co., Ltd.**,
Shenzhen (CN)

(**) Term: **15 Years**

(21) Appl. No.: **35/518,421**

(22) Filed: **Aug. 8, 2023**

(80) **Hague Agreement Data**

Int. Filing Date: **Aug. 8, 2023**

Int. Reg. No.: **DM/231485**

Int. Reg. Date: **Aug. 8, 2023**

Int. Reg. Pub. Date: **Sep. 22, 2023**

(30) **Foreign Application Priority Data**

Jun. 29, 2023 (CN) 202330402945.6

(51) **LOC (15) Cl.** **14-02**

(52) **U.S. Cl.**

USPC **D14/344**

(57)

CLAIM

The ornamental design for a smartwatch as shown and described.

DESCRIPTION

1. Smartwatch

1.1 Front view

1.2 Back view

1.3 Left view

1.4 Right view

1.5 Top view

1.6 Bottom view

1.7: Orthographic view

1.8: Orthographic view

(Continued)

The broken lines in the reproductions depict portions of the smartwatch that form no part of the claimed design.

1 Claim, 8 Drawing Sheets
